UNITED STATES PATENT OFFICE.

BLANCHE REDFIELD CALLANDER, OF MALONE, NEW YORK.

DESIGN FOR A CORSAGE-BOUQUET HOLDER.

54,594.

Specification for Design.

Patented Mar. 9, 1920.

Application filed April 1, 1919. Serial No. 286,763. Term of patent 3½ years.

To all whom it may concern:

Be it known that I, BLANCHE REDFIELD CALLANDER, a citizen of the Dominion of Canada, residing at Malone, in the county of Franklin and State of New York, have invented a new, original, and ornamental Design for a Corsage-Bouquet Holder, of which the following is a specification, reference being had to the accompanying drawing, forming part thereof.

The figure is a perspective view of a corsage bouquet holder, showing my new design.

What is claimed is—

The ornamental design for a corsage bouquet holder, as shown.

BLANCHE REDFIELD CALLANDER.
